ROTARY VALVE FOR INTERNAL COMBUSTION ENGINES

Charles W. Hall, Denver, Colo., assignor to
E. Clifford Heald, Denver, Colo.

Application July 1, 1940, Serial No. 343,386

12 Claims. (Cl. 123—190)

This invention relates to a rotary valve for internal combustion engines and has for its principal object the elimination of all poppet valves, valve stems, cam shafts, valve springs, valve grinding operations, burned out valves, and other disadvantages of the present poppet valve systems in internal combustion engines.

Other objects of the invention are to provide a rotary valve to replace the usual poppet valve which will be self-grinding, that is, one which will maintain its seal continuously throughout the life of the engine regardless of wear; to provide improved means for sealing, cooling, and lubricating the cylinder face of the rotary valve; to provide a comparatively short streamlined gas passage through a valve of this character and to provide means whereby the spark plug may be mounted in the valve so that it will be subjected to the combustion heat and flame for only a short interval thereby increasing the life and effectiveness of the plug.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a vertical section through the head of a typical internal combustion engine cylinder illustrating one form of the improved rotary valve in place thereon.

Figs. 2 and 3 are horizontal sections through the mechanism of Fig. 1, taken on the lines 2—2 and 3—3, respectively.

Fig. 4 is a longitudinal section through the head of a typical cylinder illustrating a second form of the improved rotary valve in place thereon.

Fig. 5 is a cross section, taken on the line 5—5, Fig. 4.

Fig. 6 is a detail view illustrating the cylinder face of the rotary valve of Fig. 4.

Fig. 7 illustrates the head of a typical cylinder with a third form of the rotary valve in place thereon.

Fig. 8 is a cross section, taken on the line 8—8, Fig. 7.

In the drawings typical parts of an internal combustion engine have been indicated by numerals as follows: cylinder 10, motor block 11, 53

piston head 12, water jacket 13, spark plug opening (in Figs. 1 to 4 inclusive) 14. In the specification, the flat face of the rotary valve in all forms which faces toward the cylinder is referred to as the "cylinder face." The curved surface of the valve is referred to as the "conical face."

In the first form of the invention, a valve head 15 is secured on the motor block 11 and provided with a conical valve cavity 16 in which a conical 10 rotary valve 17 is rotatably mounted. The valve head 15 about the cavity 16 is hollow and provided with water cooling passages 18. In an air cooled engine, of course, the water passages would be eliminated and the valve cavity would be directly exposed to the cooling air.

The valve has the same contour as the valve cavity and, as the former rotates, it wears itself into a perfect seat in the cavity. The upper extremity of the rotary valve is formed with a stub 20 shaft 19 extending beyond the head 15. The shaft extends through a suitable bushing 20 in the head and carries a drive sprocket or gear 21 keyed thereon, by means of which it is rotated at one-half engine speed during the operation of 25 the engine.

Power may be supplied to the gear 21 in any desired manner. As illustrated, it is driven from a combination spur and bevel gear 22 journaled on the valve head. The gear 22 is driven from 30 bevel gears on a valve shaft (not shown) extending throughout the length of the engine. The valve 17 is constantly urged into its seat by means of a compression spring 23 compressed between the gear 21 and a spring disc 24 by means of an 35 adjustable compression nut 25.

The valve head is provided with two ports, herein designated an exhaust port 26 and an intake port 27. The exhaust port 26 communicates between the side of the head and the side of the 40 valve cavity. The intake port 27 communicates between the top of the head and the side of the valve cavity at a point above the exhaust port 26. The point of exit of these ports from the head is unimportant as it might be more convenient in some designs to bring the port 27 through the side of the head and the port 26 through the top thereof. It is important, however, that they communicate through the conical side wall of the cavity 16 at different planes of 45 elevation therein.

The valve 17 is provided with an intake passage 28 and an exhaust passage 29. The intake passage leads from a point which will register with the intake port 27 in the side wall of the valve, to an eccentrically positioned outlet in the

cylinder face of the valve. The exhaust passage 28 extends from a position in the conical face of the valve which will register with the exhaust port 26 to a concentric position on the cylinder face of the valve, in circumferential alignment with the outlet of the passage 28. These passages alternately register with a cylinder port 38 communicating with the cylinder 10, and are thus, alternately placed in communication with the cylinder.

An axially expansible sealing ring 31, acting in combination with a conical sealing ring 32 positioned in the block 11, seals the cylinder port to the valve ports. The sealing ring 31 is movably carried in a sealing plate 33 positioned between the valve and the block.

The plate 33 does not rotate with the valve but is prevented from rotation by means of an eccentrically mounted button 34. The button 34 is eccentrically mounted on a gear shaft 35 of a drive gear 36. The gear 36 is driven from a small pinion 37 on a stub shaft 38 mounted in the rotary valve. The button 34 is rotatably mounted in a circular receiving opening in the valve plate 33 so that as the button rotates on its eccentric path it imparts a gyratory reciprocation to the valve plate. This prevents the valve plate from remaining in any set relation to the valve so as to prevent the formation of circular scratches or grooves thereon and acts to uniformly grind or wear all surfaces to a perfect seal.

The button 34 is continuously urged upwardly against the valve plate by means of a compression spring 39 and acts to hold the plate tightly against the bottom of the valve at all times. The axially expanding ring 31 forces itself against the rotary valve and acts to force the conical sealing ring constantly against its seat, thus providing a perfect seal. The valve plate constantly reciprocates the sealing ring 31 to prevent it from wearing a circular path or groove in the valve.

Lubrication is constantly supplied to the valve plate and its chamber under pressure through a lubricating port 40. The plate is drilled to allow the lubrication to flow to the button 34 and upwardly through the contact face of the plate. During operation, the intake passage 28 aligns with the cylinder port and the intake port at each alternate revolution of the engine crank shaft and similarly the exhaust passage 28 aligns with the cylinder port and the exhaust port at each alternate intermediate revolution. Thus, the engine itself functions as the usual four-cycle engine with all poppet valves, cam shafts, etc. eliminated.

In the form of Figs. 4, 5, and 6 the same principle of operation is employed. In this form, a valve head 41 is attached to the cylinder block over a cylinder port 42. The valve head provides a conical seat for a conical rotary valve 43. In this valve, however, an intake passage 44 extends from an axial position at the top of the valve to an eccentric position at the cylinder face of the valve. The exhaust passage, shown at 45, is similar to the one of the previously described form and communicates between the conical face of the valve and an eccentric position on the cylinder face thereof, both passages being streamlined.

In this form, the valve is driven from a gear 46 secured to a hollow trunnion 47 projecting from the top of the valve and containing the intake passage. The gases are conducted to the passage from any suitable manifold 48 which is

rotatably sealed to the valve by means of suitable packing 49. A thrust bearing 50 absorbs both the axial and diametric thrusts to relieve both the pressure and friction on the conical face of the valve. The valve is constantly urged upwardly toward its conical seat by means of a valve plate 51 which in turn is urged upwardly by means of compression springs 52.

The valve plate 51 gyrates or reciprocates similarly to the previously described form. In this form, however, this is accomplished by turning an eccentric cylindrical cam surface 53 on the bottom edge of the valve and forming a cam follower flange 54 on the valve plate which will ride against this eccentric cam surface to impart a reciprocation to the valve plate as the valve rotates. The flange 54 of the valve plate is constantly forced against the cam surface by means of an adjustable compression spring 55.

A sealing ring 56 is mounted in the valve plate and reciprocates therewith. This ring is urged upwardly by means of a multiple, conical, axially and laterally expansible ring 57 which acts thereagainst. The operation of this form is similar to the first form.

In the third form of the invention shown in Figs. 7 and 8, a hollow rotary valve 58 is employed. This valve has rounded conical sides fitting into a rounded conical seat in the valve head 59. It is constantly urged upwardly in its seat by means of a spring 60, the thrust of which is absorbed by a thrust bearing 61. This form of the valve is shown applied to a two cycle engine. Such engines have their exhaust ports through the cylinder wall adjacent the bottom of the piston stroke so that the rotary valve at the piston head need only accommodate the intake gases. For this purpose, an intake passage 62 is formed in the rotary valve from the cylinder face through the inclined side wall thereof at a position to register with an intake port 63. The valve in this form rotates at crank shaft speed so that the passage 62 will align between the port 63 and a cylinder port 64 at each crank shaft revolution.

A sealing plate 65 is positioned against the cylinder face of the valve. The sealing plate is provided with a stub 66 extending into an eccentrically positioned receiving bearing in the valve. Thus as the valve rotates this eccentric position of the receiving opening will swing the stub 66 about a circular orbit imparting a gyrating motion to the sealing plate to prevent it from wearing circular grooves in the valve surface and to uniformly distribute the lubricating oil thereover. The sealing plate is prevented from rotation by means of a tongue 67 projecting therein and is lubricated similarly to the previously described form. A sealing ring 68 passes through and gyrates with the plate. An expanding split ring 69 acts against the ring 68 to hold it against the cylinder face of the valve.

A spark plug 70 is contained within the valve and is threaded into the bottom thereof, there being a gas passage 71 opposite the spark gap of the plug. The plug is positioned substantially diametrically opposite the passage 62 so that it will register with the cylinder port 64 at the time the explosion is to occur in the cylinder. It will immediately move away from this passage after ignition so that it will not become fouled with combustion products nor damaged by the heat. Current is conducted to the plug 70 through a suitable conductor 72 leading

to a contact button 73 supported in an insulating bushing 74 in the top of the valve. Current may be conducted to the button 73 in any desired manner. This construction prevents the plug from ever becoming sufficiently overheated to cause pre-ignition.

It is desired to call attention to the fact that with tapered construction of the valve a full and close contact is had over the full tapered face at all times. This contact may be much closer than with a cylindrical valve since expansion of the valve or contraction of the case need not be accommodated for. Any expansion of the valve simply forces it further down in its tapered seat so that it cannot seize or stick. This close contact provides a highly efficient heat transfer from the valve to the housing to keep the valve relatively cool at all times. The close contact also serves to more completely seal the passages against gas leakage without packing or sealing devices of any kind.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. In combination with an internal combustion engine having a conical rotary valve for the cylinder thereof, a cylinder port communicating with said cylinder, the conical rotary valve having its axis to one side of said port; a flat face on said valve normally closing said port; a passage through said valve from an eccentric position on the flat face to a position on the conical wall thereof; and a second passage through said valve from a point on the flat face in register with said cylinder port to an outlet in the conical wall of said valve above the outlet of the first passage.

2. In combination with an internal combustion engine cylinder comprising: a cylinder port communicating with said cylinder; a conical rotary valve for said engine having its axis to one side of said port; a flat face on said valve normally closing said port; a passage through said valve from an eccentric position on the flat face to a position on the conical wall thereof; and an ignition device carried by said valve so as to align with the cylinder port at selected times as said valve rotates.

3. The combination with a rotary valve having a sealing plate against one of its faces, of means for imparting a reciprocatory movement to said plate as said valve rotates.

4. In a rotary valve of the type having a sealing plate against one of its faces, an eccentric member; means for rotating said eccentric member in consequence of the rotation of said valve; and means for causing the eccentric rotation of said member to gyrate said valve as the latter rotates.

5. Means for gyrating a sealing plate against a rotary valve comprising; an eccentrically mounted button extending into said plate; and means for rotating said button to cause said plate to follow the eccentricity thereof.

6. Means for gyrating a sealing plate against a rotary valve comprising; a button extending into said plate; a gear eccentrically connected to said button; a gear driven by said valve in mesh with the gear on the button for eccentrically rotating the latter from the rotation of said valve and means for preventing rotation of the sealing plate.

7. Means for gyrating a sealing plate against a rotary valve comprising; a button extending into said plate; rotating means for said button for eccentrically rotating the latter from the rotation of said valve; means for holding the sealing plate from rotation and resilient means for urging said button against said plate.

8. Means for gyrating a sealing plate against a rotary valve comprising; a stud extending from said plate into an eccentric socket in said valve so that as said valve rotates said stud will gyrate said plate; and means for preventing rotation of said plate.

9. Means for gyrating a sealing plate against a rotary valve comprising; an eccentric surface formed on said valve; and means on said plate for engaging said surface to impart a gyrating motion to said plate as said valve rotates.

10. Means for gyrating a sealing plate against a rotary valve comprising; an eccentric surface formed on said valve; means on said plate for engaging said surface to impart a gyrating motion to said plate as said valve rotates; and a spring for maintaining said latter means in contact with said eccentric surface.

11. In combination with an internal combustion engine, a rotary valve for controlling the flow of gases to said engine, a sealing plate for said valve; means for holding said sealing plate against one of the faces of said valve, there being a port through said sealing plate for the gases, a sealing ring sealing said port to said valve, and means for imparting movement to said plate as said valve rotates so that both the plate and the sealing ring will be moved.

12. In combination with an internal combustion engine cylinder comprising: a cylinder port communicating with said cylinder; a conical rotary valve for said engine having its axis to one side of said port; a flat face on said valve normally closing said port; a passage through said valve from an eccentric position on the flat face of said valve to a position on the conical wall thereof; a hollow concentrically positioned shaft extending from the apex of said valve for imparting rotation thereto; and a second passage extending from an eccentric position on the flat face of said valve outwardly through said hollow shaft.

CHARLES W. HALL.
